PRINTING PLATE COATING MACHINE

Lawrence B. Corbett, Binghamton, Philip Tatusko, Endicott, and Donald R. Pratt, Apalachin, N. Y., assignors to International Business Machines Corporation, New York, N. Y., a corporation of New York

Application October 17, 1950, Serial No. 190,616

8 Claims. (Cl. 118—230)

1

This invention relates to a device for re-inking the surface of flat printing plates and more particularly to means for applying ink around the sides of etched recessed surfaces of flat engraved printing plates.

In the art of photoengraving, a flat sheet of copper, zinc or other suitable material is cleaned and coated with a sensitized solution. This coating is exposed through a prepared negative to obtain the desired printing or design on the metal. When the metal plate is developed, the portions of the coating that were exposed through the transparent areas of the negative adhere to the metal plate and form a resistance to the action of etching acid while the portions under the opaque areas of the negative wash away in development and these are the areas that are etched away by the acid.

After a plate is prepared in this manner, it is etched to a depth generally of .001 to .002 of an inch. If the etching was to be continued at this point, the acid would begin to undercut the walls or sides of the various etched characters and produce ragged edges. To prevent this sort of undercutting the sides of the etched characters are usually built up and protected from etching by a rather long and tedious powdering process.

This process which is in common use today consists of thoroughly drying the etched plate and then putting it into a box containing dragon's blood powder. The entire plate is liberally covered with this powder and then the excess is lightly brushed off. It is essential that brushing be in one direction only so as to pack the powder against one side of the etched characters. The brushed plate is then heated until the powder melts. When the powder fuses together, the plate is quickly cooled causing the powder to harden and become impervious to acid. This complete process is manually repeated in three more directions to build up the four sides of the various etched characters and obviously this is a long and laborious process particularly in view of the fact that it is required each time the depth of the etching is to be increased.

It is the intention of the present invention to facilitate the above method now being used for strengthening the base of etched characters or the like on photoengraved printing plates and to do the operation in less time and with more positive results. We propose to employ a device which will automatically wipe a layer of ink on the etched plate in at least four directions to completely surround the base of the etched characters. Then the engraved plate is simply removed from the device, an asphaltum powder is sprinkled thereon and the excess powder which

2

does not adhere to the ink is blown off. The plate is then baked to harden the ink and powder together. In this manner the four cumbersome hand operations are eliminated and a much more effective job is done.

In accordance with this it is the main object of the invention to provide a device which can be utilized to wipe a relatively uniform layer of ink or the like on the etched side walls in a flat photoengraved plate.

It is a further object of the present invention to provide a device for wiping a relatively uniform layer of ink or the like on the etched side surfaces of a flat photoengraved plate which includes means for causing said ink to be wiped on each edge of the etched characters so that the ink will be wiped down each side of the character and be deposited at the base.

A still further object is to provide a device for wiping a relatively uniform layer of ink or the like on the etched side surfaces of a photoengraved plate which includes means for indexing said plate as it is being inked so that ink may be wiped against all sides of the etched characters during one operational run of the device.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a perspective view showing the general outline of the machine.

Fig. 2 is an end view of the inking unit showing the arrangement of the inking roller and the cooperating spreading rollers.

Fig. 3 is a plan view of the machine with the inking unit at the extreme right end in position to commence an inking run.

Fig. 4 is a sectional view taken on line 4—4 of Fig. 3 and shows the constructional details of the inking unit and also a portion of the indexing mechanism.

Fig. 5 is a sectional view taken on line 5—5 of Fig. 3 and shows constructional details of the turntable for the photoengraved plate and the indexing mechanism therefor.

Referring to the general outline of the machine as shown in Fig. 1 and also to Fig. 5, the machine comprises a stationary table which consists of a top plate 10, two side angle pieces 11, two end plates 12 and a bottom plate 13. The top plate 10 is attached to the side pieces 11 by bolts 14 for removal purposes whereas the end plates 12 and bottom plate 13 may be welded together and

to said side plates. The table is supported in the usual manner by four legs 15 which are fastened thereto by the brackets 16 and bolts 17.

Two turntables 18 and 19 are rotatably supported by said stationary table, said turntables each having a spindle 20 which extends through a ball bearing 21 mounted in a bearing block 22 attached to the underside of the top plate 10. The spindles 20 extend further through a pair of ball bearings 23 mounted in bearing blocks 24 attached on the underside of bottom plate 13. A nut 25 on each spindle 20 is flush against the underside of ball bearing 23 to act as further support. As shown in Fig. 1, the turntable designated 18 has three crossing grooves 26 cut across its top surface. Each one of these T-shaped grooves 26 is adapted to receive a small adjustable block 27 which can be moved along the groove and which can also be secured against movement by tightening a set screw 28 into a lower binding block. The turntable 18 serves as a support for the photo-engraved plate 29 and the adjustable blocks 27 are used to secure said plate 29 in position on said turntable 18 preparatory to inking. The other turntable 19 functions to support a supply of ink which will be taken up by an ink roller unit and spread on the surface of the engraved plate 29 in a manner to be described.

Drive mechanism

Referring to Fig. 1, a reversing motor 30 is mounted below the stationary table and on a support plate 31 which is attached to the legs 15. The motor shaft 32 extends through a gear box 33 and has attached on its free end a pulley 34 which through a belt 35 drives a pulley 36 and worm shaft 37. The worm shaft 37 is journaled at each end of the stationary table in a housing 38 which is attached to the inside of the end plate 12 by means of the bolts 39 (see Fig. 4).

The worm shaft 37 extends through a worm block 40 attached to the underside of a plate 41 as shown in Fig. 4. The plate 41 is the bottom plate of a carriage unit which is formed by attaching two side plates 42 to the bottom plate by means of the bolts 43 as shown in Fig. 5. The side plates 42 are further supported at the top by means of two rods 43a fastened between them. Attached to each side plate 42 by means of the bolts 44 are two pairs of rollers 45 adapted to straddle a bar 46 fixed, by means of the bolts 47, along the entire length of each side plate 42 of the stationary table. It will be apparent that as the worm shaft 37 is driven by the motor 30, the carriage unit will be driven along the bar 46 by motion imparted to the attached worm block 40. The direction of travel of the carriage unit will depend upon the direction of rotation of the worm shaft 37 and accordingly there is provided at each end of the stationary table a micro-switch 48 so that as the carriage unit reaches one end of the stationary table one of the micro-switches will be operated by rear plate 42 and closed to reverse the rotation of said motor 30 and consequently said worm shaft 37. As a result the carriage unit will reverse its direction of travel and move to the opposite end of the stationary table. Thus, with the motor turned on, the carriage unit will travel back and forth along the stationary table actuating a micro-switch 48 at each end of the table to reverse its direction of travel.

Inking mechanism

As was previously mentioned, a supply of ink 75 provided for each stud 66 so that the pressure

is placed on the surface of turntable 19 which is to be taken up and spread over the etched surfaces of the engraved plate. To perform this function there is mounted in the carriage mechanism an inking roller unit which wipes across the surfaces of the turntables 18 and 19 as the carriage traverses back and forth along the stationary table. The inking roller unit comprises a shaft 49 on which is fixed an inking roller 50 and a gear 51 as shown in Fig. 3. Each end of the shaft 49 is journaled in a ball bearing 52 and bearing block 53 which fits into a groove in the side plates 42 of the carriage mechanism (see Figs. 1 and 2). The bearing blocks 53 are held down in said grooves by means of bars 54 bolted over the tops of the side plates 42 by bolts 55 as shown in Fig. 2. A pair of springs 56 extending between suitable recesses in the side plates 42 and bearing blocks 53 serve to push said bearing blocks 53 against the set screws 57. Thus, by adjusting the set screws 57, the inking roller 50 may be adjusted vertically with respect to the surfaces of the turntables 18 and 19 to either increase or decrease the amount of ink transferred.

To obtain the best results it has been found that the inking roller 50 should exert a wiping action across the surface of the flat plate so that the ink will be scraped along the edges of the etched characters and forced down along the sides to the base. To accomplish this the inking roller is caused to rotate at a different rate of speed than the linear speed of the carriage unit. In the present embodiment of the invention, means are provided for causing the inking roller 50 to rotate at a faster rate of speed than the linear speed of the carriage unit, but it is to be understood that similar means may be introduced into the machine to cause said inking roller 50 to rotate at a slower rate than the linear speed of the carriage unit.

As the inking roller 50 is carried back and forth by the carriage mechanism it is also caused to revolve by means of a gear rack 58 attached to the top plate 10 of the stationary table and which meshes with the gear 51 on shaft 49. The circumference of the gear 51 is smaller than the circumference of the inking roller 50 causing said roller 50 to rotate at a faster rate than the linear speed at which the carriage mechanism travels. As a result, roller 50 exerts a wiping action on the surfaces of the turntables 18 and 19 and this is quite important because as roller 50 wipes across the edges of the etched surfaces on the engraved plate the ink will be forced down along the sides of the characters and form around the base to prevent future applications of etching acid from undercutting the characters.

In order to perform a neat and uniform inking job it is necessary that the layer of ink picked up by the roller 50 be spread uniformly about the roller itself and also that any impressions left in the roller, due to a previous pass over the engraved plate, be removed. Accordingly there is provided, as shown in Fig. 4, a pair of erasing and spreading rollers 59 fixed on auxiliary shafts 60 which are journaled at each end in the hinges 61 pivotally mounted on studs 62 fixed to the side plates 42. Each hinge 61 is provided with a recess 63 into which extends a compression spring 64. The other ends of the springs 64 extend into spring retainers 65 which are connected to threaded studs 66 mounted in support blocks 67 which are attached to the side plates 42 of the carriage mechanism by bolts 68. A nut 69 is provided for each stud 66 so that the pressure

exerted against the hinges 61 by the springs 64 may be varied to adjust the pressure exerted on the inking roller 50 by the spreading rollers 59. By adjusting the degree of pressure exerted by rollers 59 and regulating the position of the inking roller 50 through set screws 57, the application of the ink to the surface of the engraved plate may be well controlled.

Indexing mechanism

One of the features of the invention is to provide means for applying ink to all sides of the etched characters on the engraved plate effectively and in a minimum amount of time. To accomplish this there is provided an indexing mechanism for rotating the turntables 18 and 19 intermittently as the carriage sweeps back and forth.

Referring to Figs. 3 and 5, a flanged ring 70 is mounted on the threaded bottom portion of each spindle 20 and is held fast thereto by means of a lock nut 71. Loosely mounted on each flanged ring 70 for coaction therewith is a sleeve 72 which encircles a series of four notches 73 spaced 90° apart around the periphery of said ring 70 as shown in Fig. 3. With the sleeve 72 mounted on said ring 70 each of said notches 73 is adapted to hold a small steel ball 74 and due to the shape of the notches 73 a clutching action is effected in that if the sleeve 72 is caused to rotate counter-clockwise, Fig. 3, the balls 74 will lodge in the small end of the notches and create sufficient friction between the sleeve and ring to cause said ring to also rotate counter-clockwise. However, if the sleeve 72 should be rotated in a clockwise direction the balls 74 will lodge in the large end of the notches thereby relieving the friction between the sleeve and ring and allowing said ring to remain stationary while the sleeve rotates clockwise.

The drive for the sleeves 72 is taken from the movement of the carriage unit through a pair of rods 75 and 76. As seen in Fig. 3, the rod 75 is connected to sleeve 72 for the turntable 18 through an adapter 77 and extends towards the right hand end of the machine whereas the other rod 76, although connected to sleeve 72 on the turntable 19 in the same manner through adapter 78, extends towards the left hand end of the machine. Attached to the underside of the top plate 10 of the stationary table are two brackets 79 and 80, the bracket 79 being attached at the right end of the machine and extending down towards the path of rod 75, as shown in Fig. 5, and the bracket 80 similarly attached at the left end of the machine and extending down towards the path of rod 76. Fixed to the bottom of each bracket 79 and 80 is a block 81 through which the rod, in alignment therewith, slidably passes, as shown in Fig. 4.

As seen in Figs. 3 and 5 there are fixed to the top of plate 41 of the carriage unit, two blocks 82 and 83. The block 82 is in alignment with rod 75 and in the path of a disk 84 fixed on said rod while the block 83 is in alignment with rod 76 and in the path of a disk 85 fixed on said rod 76. Extending between the disk 84 and the block 81 for rod 75 and between disk 85 and the block 81 for the rod 76 are coil springs 86 which tend to force said rods in a direction so that the stop disks 87, mounted on the free ends thereof, will be flush against the sides of the related blocks as one is against block 81 as shown by the position of rod 76 in Fig. 3.

To clarify the operation of the indexing mech-

anism, assume that the carriage unit is at the extreme right end of the machine as shown in Fig. 3. When the reversing motor 30 is started, the carriage unit will commence to move toward the left end of the machine carrying the blocks 82 and 83 with it. Upon movement of the carriage to the left, the block 82 will allow the spring 86 to force rod 75 to the left until stop disk 87 is against the block 81. The sleeve 72 for turntable 18 will be driven in a clockwise direction but, as previously explained, clockwise movement of sleeve 72 will not clutch ring 70, and so turntable 18 does not index yet. As the carriage unit approaches the extreme left end of the machine, the block 83 will cam disk 85 and rod 76 toward the left, causing the sleeve 72 to rotate in a counterclockwise direction. Counterclockwise movement of the sleeve 72 causes the ring 70 to be clutched in and the turntable 19 will index in a counterclockwise direction until the carriage stops against micro-switch 48. It follows then that when the carriage unit reverses and moves toward the right end of the machine, the sleeve 72 and ring 70 on turntable 19 will be de-clutched and turntable 19 will not move whereas block 82 will cam rod 75 to the right causing a counterclockwise rotation of sleeve 72 and ring 70 on the turntable 18 to rotate said turntable 18 to index it in a counterclockwise direction until the carriage closes micro-switch 48 at the right end of the machine.

In the present embodiment of the machine, the turntables 18 and 19 will each be indexed a total of 45° for every two passes of the carriage unit, the inking table 19 being indexed 45° on the first pass of the carriage from right to left and turntable 18 being indexed 45° on the second or return pass from left to right. The time required to re-ink the engraved plate in 8 different directions is only slightly over 2½ minutes after which it takes about 2 minutes to sprinkle the powder on and 2 more minutes for baking making a total time of approximately 7 minutes. This is a great improvement over the hand method of powdering in only 4 directions which requires four separate baking and cooling operations and consumes a total time of about 20 minutes for each plate. In addition, the present invention provides means for finely adjusting the amount of ink applied and for maintaining the application of said ink uniform for as many operations as desired. By the hand method the uniformity of results is dependent entirely on the skill of the operator.

While there have been shown and described and pointed out the fundamental novel features of the invention as applied to a single modification, it will be understood that various omissions and substitutions and changes in the form and details of the device illustrated and its operation may be made by those skilled in the art without departing from the spirit of the invention. It is the intention, therefore, to be limited only as indicated by the scope of the following claims.

What is claimed is:

1. In a machine of the class described, a stationary table, a turntable revolvably mounted on said table for holding a supply of ink, a second turntable revolvably mounted on said table for holding a flat plate which is to be inked, a movable carriage unit straddling said stationary table, means to move said carriage unit back and forth along said stationary table and across both of said turntables, means under control of said movable carriage for indexing said turntables, a roller unit fixed on said movable carriage and

having an inking roller rotatable thereon, and means effective upon movement of said carriage unit across both of said turntables for causing said inking roller to rotate at a different rate than the linear speed of the carriage unit whereupon said inking roller will have the effect of wiping across the surfaces of said turntables.

2. In a machine of the class described, a stationary table, a turntable revolvably mounted on said table for holding a supply of ink, a second turntable revolvably mounted on said table for holding a flat plate which is to be inked, a movable carriage unit straddling said stationary table, means to move said carriage unit back and forth along said stationary table and over both of said turntables, means under control of said movable carriage for indexing said turntables, a roller unit fixed on said movable carriage and having an inking roller rotatable thereon, a gear integral with said inking roller and having a smaller circumference, and a gear rack on said stationary table and in mesh with said gear to cause the inking roller, upon movement of said carriage unit over both of said turntables, to rotate at a faster rate of speed than the linear speed of said carriage.

3. In a machine of the class described, a stationary table, a turntable revolvably mounted on said table for holding a supply of ink, a second turntable revolvably mounted on said table for holding a flat plate which is to be inked, a movable carriage unit straddling said stationary table, means to move said carriage unit back and forth along said stationary table and across said turntables, means under control of said movable carriage for indexing said turntables, a roller unit fixed on said movable carriage and having an inking roller rotatable thereon, means effective upon movement of said carriage unit across said turntables for causing said inking roller to rotate at a different rate than the linear speed of the carriage unit whereupon said inking roller will have the effect of wiping across the surfaces of said turntables, and means for adjusting said inking roller vertically with respect to said turntables to increase or decrease the wiping action.

4. In a machine of the class described, a stationary table, a turntable revolvably mounted on said table for holding a supply of ink, a second turntable revolvably mounted on said table for holding a flat plate which is to be inked, a movable carriage unit straddling said stationary table, means to move said carriage unit back and forth along said stationary table and over said turntables, means under control of said movable carriage for indexing said turntables, a roller unit fixed on said movable carriage and having an inking roller rotatable thereon, means effective upon movement of said carriage unit over said turntables for causing said inking roller to rotate at a different rate than the linear speed of the carriage unit whereupon said inking roller will have the effect of taking ink off the surface of said first turntable and wiping the ink across the surface of the plate on said second turntable, and means coacting with the periphery of said inking roller for distributing evenly the ink deposited thereon.

5. In a machine for inking a flat plate, a stationary table, a turntable revolvably mounted on said table for holding a supply of ink, a second turntable revolvably mounted on said table for holding said flat plate which is to be inked, a movable carriage unit straddling said stationary table, means to move said carriage unit back and

forth along said stationary table and over both turntables, a roller unit fixed on said movable carriage for transferring ink from said first turntable to the flat plate on said second turntable upon movement of said carriage, and indexing means to index one of said turntables upon movement of said carriage in one direction and to index the other turntable upon movement of said carriage in the opposite direction.

6. In a machine of the class described, a stationary table, a turntable revolvably mounted on said table for holding a supply of ink, a second turntable revolvably mounted on said table for holding a flat plate which is to be inked, a movable carriage unit straddling said stationary table, means to move said carriage unit back and forth along said stationary table and across both turntables, a roller unit fixed on said movable carriage to transfer ink from said first turntable to the flat plate on said second turntable upon movement of said carriage, a uni-directional clutch operatively mounted on each of said turntables, a yieldable connection between each clutch and a bracket attached to said stationary table, spring operated means normally urging said yieldable connections and said clutches in a de-clutching direction, and a pair of cam members attached to said movable carriage and arranged to coact with said spring operated means to clutch in one of said turntables and index the same upon movement of said carriage in one direction and to de-clutch said indexed turntable and clutch in said other turntable to index the same upon movement of said carriage in the opposite direction.

7. In a device for reinking an etched plate, a main table, an ink supply turntable mounted on the top of said table, a plate supporting turntable also mounted on the top of said table, an inking roller for wiping over the tops of both said turntables, a frame for holding said inking roller, spreading rollers rotatably mounted on said frame and cooperating with said inking roller to erase impressions therein and spread the ink, means for reciprocating said frame back and forth along said table and over both of said turntables on each reciprocation, and means under control of said frame for rotating said turntables alternately by each reciprocation of said frame.

8. In a device for re-inking an etched plate, a turntable, means for securing said plate to the top of said turntable, means for rotatably indexing said turntable step by step, an inking roller, means for applying ink to said roller, and means for rolling said roller over said plate with a linear motion, said rolling means including means for turning said inking roller at a different speed than the speed of said linear motion over the plate to wipe ink thereon in alternation with the operation of said means for rotatably indexing said plate.
